Patented Sept. 29, 1970

218,869

CASING FOR HAIR CURLING MACHINE

Norman J. Mercer, 42 Broadway,
New York, N.Y. 10004

Filed Jan. 28, 1969, Ser. No. 15,536

Term of patent 14 years

Int. Cl. D28—03

U.S. Cl. D86—10

FIG. 1

FIG. 2

FIG. 3

FIG. 4

FIG. 5

FIG. 1 is a top plan view of a casing for hair curling machine showing my new design.

FIG. 2 is a front elevational view.

FIG. 3 is a right side elevational view, the left side being substantially a mirror image thereof.

FIG. 4 is a back elevational view.

FIG. 5 is a bottom plan view.

I claim:

The ornamental design for a casing for hair curling machine, as shown and described.
